UNITED STATES PATENT OFFICE.

TOWNSEND W. BURT, OF HEMPSTEAD, NEW YORK.

MANDREL PRESS.

Application filed May 25, 1922. Serial No. 563,610.

To all whom it may concern:

Be it known that I, TOWNSEND W. BURT, a citizen of the United States of America, residing at Hempstead, L. I., in the county 5 of Nassau and State of New York, have invented certain new and useful Improvements in Mandrel Presses, of which the following is a specification.

This invention relates to machines for 10 removing gears, wheels and the like from their shafts, or for mounting the same on their shafts.

One of the objects of this invention is to devise a machine which may be used for 15 either of the above named purposes with a minimum amount of changing.

A further object of the invention is to construct a mandrel press which is more 20 simple and quicker to operate than the presses at present in use and at the same time of less cost.

Referring to the drawings in which what 25 I now consider the preferred form of my invention is shown;

Fig. 1 is a front elevation, partly in section of my preferred form of press.

Fig. 2 is a side elevation of the same.

Fig. 3 is a section on line 3—3 looking down with the work removed.

Fig. 4 is a detail showing the attachment for employing the machine to place a gear upon a shaft.

Fig. 5 is a front elevation of a modified form of removable foot rest.

My apparatus is shown as made up of a base 1 on which is hinged a hand operated lever 2 which may be forked at the base so as to have two spaced ears 3 and 4, through which extend bolts 5 and 6 secured between 35 pairs of upstanding ears 7 and 8 on the base. An open frame 9 is shown as hinged at 10 and 11 on said lever 2 at points comparatively close to the pivotal points of lever 2 so that a large leverage will be 40 exerted to move said frame 9 downwardly on rotation of the lever 2 in a clock-wise direction in Fig. 2. The frame 9 is shown as passing upwardly on each side of the work-holder or table 12. Said table is held 45 in spaced relation to the base 1 as by means of a tube or hollow column 13. The work-holder at opposite sides thereof may be cut away to form opposite shoulders 15 and 16 to limit the angular movement of the frame 50 9 about pivots 10 and 11. If desired, an adjustable threaded stop 17 may be pro-

vided on one of the shoulders so that it may be positioned accurately to maintain the frame when in its forward position exactly vertical, i. e., directly over the work. 60 The frame 9 is shown as extending above the work-holder 12 and provided adjacent its upper end with cross piece 18. Said piece may be adjustably mounted in the frame 9 as by means of set screws or bolts 65 19 which may be inserted in any one of the plurality of holes 20 and 21 in the opposite legs of the frame. Movably mounted in said cross piece 18 is the work engaging member 22. Said member may have any 70 suitable adjustable mounting in the frame 18 but is shown as provided with ratchet teeth 23 with which a double acting pawl 24 cooperates. Said pawl is shown as pivoted to member 18 at 25 and is biased 75 so that either its lower tooth 26 yieldingly engages the ratchet as shown in Fig. 1 or its upper tooth 27 engages said ratchet by means of the spring 28 and link 29 which is pivotally and slidably mounted on pin 29'. When in the position shown in the drawings, it is obvious that the pawl will 80 permit ready downward movement of the ratchet bar 22 to engage the work, but will prevent upward movement thereof. If 85 on the other hand the pawl is tripped by the thumb-piece 30, the reverse is true. The work is shown in this instance as a gear 31 from which it is desired to remove its shaft 32. In placing the work on the table, 90 the frame 9 may be rotated to one side as indicated in dotted lines in Fig. 2. After the work is in position, the frame is rotated back to its vertical position against stop 17. The gear is merely placed on the 95 table with its shaft extending downwardly through the tube 13. In the drawings the gear is shown in the act of being placed upon the table and before it has been lowered down to rest, upon the same. After 100 thus placing the gear upon the table with the shaft thereof in the middle, the work engaging member 22 is lowered so that the reduced lower portion thereof 34 engages the shaft 32. The apparatus is now ready 105 to lower the hand lever 2 to the dotted line position in Fig. 2, if necessary, thus exerting a powerful thrust on the shaft and removing the same from the gear.

To place the gear or other member on a 110 shaft or mandrel, use is made of the adjustable foot-bar or frame 35. Said frame

is shown as adjustably and pivotally suspended from the base 1 by means of pins 37 extending through each of the uprights of said frame and resting on the base 1. The 5 said uprights extend through elongated slots 38 in said base, so that they may be moved to one side or to the center of the base. An adjustable cross-bar 40 connects the legs and serves to support the work 10 when the apparatus is used to place a pinion on a shaft as indicated in dotted lines in Fig. 1. In this case also, an attachment 41 having an annular base 42 is mounted on the lower end of member 22 to engage the 15 work (see Fig. 4). It will be readily apparent therefore, that by bringing the member 41 into engagement with the gear and supporting the shaft at the lower end by member 40, that the gear may be mounted 20 on the shaft by rotating the handle 2 downwardly, exactly as was done to remove the gear.

It should be observed that the apparatus is of such form that it need be attached to 25 a support 60 only adjacent the top thereof, as by screwing or bolting the parallel bars 61, 62 attached to the under surface plate 12 to the support. The bottom plate 1 may then remain unsupported, thus making it 30 possible to insert or remove mandrels of different lengths.

Fig. 5 shows a slight modification in the method of mounting the foot piece 35' which in this case is merely hinged to the base at 35 42'. In this figure also, an alternative means to pipe 13 for mounting the base 1 and work holder 12 in spaced relation is shown, consisting of a plurality of rods 50, 51. Said rods may be threaded and the plates adjustably held thereon by nuts 52, to provide a ready means for altering the distance between the upper and lower work holders 12 and 40' on bars 35 by means of the pins 53 (Figs. 1, 2 and 5), and holes 54.

45 In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the 50 combination and relations described, some of these may be altered and others omitted without interfering with the more general results outlined, and the invention extends to such use.

60 Having herein described my invention what I claim and desire to secure by Letters Patent is,

1. In a press, a base member, an operating lever pivoted thereon, an upper work holder 65 mounted in spaced relation to said base, a

lower work holder, means for pivotally suspending the latter from said base, and a work engaging member for operating on the work when supported on either the upper or lower holder.

2. In a press, the combination with a work holder, of an operating lever pivotally mounted below said holder, a frame pivoted on said lever whereby it may be swung over or to one side of the work and adjustable means on the frame for engaging the work.

3. In a press, a base member, an operating lever pivoted thereon, an upper work holder mounted in spaced relation to said base, a lower work holder movably mounted on said base, and a work engaging member for operating on the work when supported on either the upper or lower holder.

4. In a press, the combination with a work holder, of an operating lever pivotally mounted below said holder, a frame pivoted on said lever whereby it may be swung over or to one side of the work, means on said base for limiting the position of said member and adjustable means on the frame for engaging the work.

5. In a press, the combination with a work holder, of an operating lever pivotally mounted below said holder, a frame pivoted on said lever whereby it may be swung over to one side of the work and a ratchet bar on said frame adapted to be brought quickly into engagement with the work, whereupon said lever may be operated.

6. A portable gear or wheel mounting press comprising upper and lower bases, spacing means securing said bases in spaced relation, a pair of hinged members pivoted on the lower base and on each other, one of said members being adapted to be manually operated, a work engaging punch on the other of said members and a work holder movably mounted on said lower base.

7. In a press, the combination with a work holder, of an operating lever pivotally mounted below said holder, a frame pivoted on said lever whereby it may be swung over to one side of the work, adjustable means on said base for holding said member vertically above said work and adjustable means on the frame for engaging the work.

8. In a press, a base member, an operating lever pivoted thereon, an upper work holder mounted in spaced relation to said base, a lower work holder movably mounted on said base, a work engaging member for operating on the work when supported on either the upper or lower holder and means for securing the upper work holder to a support.

9. In a press, a base member, an operating lever pivoted thereon, an upper work holder mounted in spaced relation to said base, a lower work holder mounted on said base, and a work engaging member for op-

erating on the work when supported on either the upper or lower holder.

10. In a press, the combination with a work holder, of an operating lever pivotally mounted below said holder, a frame pivoted on said lever whereby it may be swung over or to one side of the work, means on said

base for limiting the position of said frame and means on the frame for engaging the work.

10 In testimony whereof I have affixed my signature.

TOWNSEND W. BURT.
